UNITED STATES PATENT OFFICE.

JOSEPH H. CROSBY, JR., OF JACKSONVILLE, FLORIDA.

DESIGN FOR A SPOON.

SPECIFICATION forming part of Design No. 23,983, dated February 5, 1895.

Application filed November 23, 1894. Serial No. 529,771. Term of patent 7 years.

To all whom it may concern:

Be it known that I, JOSEPH H. CROSBY, Jr., residing at Jacksonville, in the county of Duval and State of Florida, have invented and 5 produced a new and original Design for Spoons or Similar Articles, of which the following is a specification, reference being had to the accompanying drawing, forming part thereof.

10 The accompanying drawing is a view of a spoon with my design thereon, dotted lines being employed to indicate the tines of a fork to which the same design might be applied.

15 The outer end of the handle is made to represent a flag A, partially furled and beneath

this flag or adjacent thereto, is represented a coin or medal B. At some convenient place on the handle a space or panel is provided for any suitable words or inscription.

The leading feature of my design is a handle for a spoon or similar article with the representation of a flag, partially furled at its outer end and a coin or medal below or adjacent to the flag. 20

Having thus described my design, I claim— 25
The design for cutlery herein described.

JOS. H. CROSBY, JR.
